Primary Examiner — Robert Delehaney*(74) Attorney, Agent, or Firm* — Calfee, Halter & Griswold LLP(57) **CLAIM**

The ornamental design for a faucet spout and wand, as shown and described.

DESCRIPTION

FIG. 1 is a perspective view of a faucet spout and wand of the new design;

FIG. 2 is a front elevational view of the faucet spout and wand of FIG. 1;

FIG. 3 is a left side elevational view of the faucet spout and wand of FIG. 1, the right side elevational view being a mirror image thereof;

FIG. 4 is a top plan view of the faucet spout and wand of FIG. 1; and,

FIG. 5 is a bottom plan view of the faucet spout and wand of FIG. 1.

The portions of the Figures shown in broken lines are not part of the claimed design and are for illustration only.
